UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed November 1, 1922. Serial No. 598,318.

To all whom it may concern:

Be it known that I, GEORGE M. LITTLE, a citizen of the United States, and a resident of Pittsburgh, in the county of Allegheny and State of Pennsylvania, have invented a new and useful Improvement in Electric Furnaces, of which the following is a specification.

My invention relates to electric furnaces, 10 and particularly to electric-resistance furnaces.

The object of my invention is to provide a relatively simple, rugged, built-up carbonaceous resistor having a relatively high electric resistivity.

In practicing my invention, I provide a plurality of relatively thin, flat, carbonaceous plates spaced apart by current-conducting refractory members of relatively 20 small area placed therebetween adjacent one edge thereof, and means for maintaining said spacing members in their proper operative positions.

I provide also auxiliary spacing members 25 of relatively high electric resistance located between said plates adjacent another edge thereof. Resilient compressing means is provided to maintain the flat plates and the spacing members in close operative engagement with each other during the operation 30 of the furnace.

In the single sheet of drawings,

Figure 1 is a view, in vertical longitudinal section, of an electric-resistance furnace comprising the device embodying my invention,

Fig. 2 is a view, in vertical lateral section, taken on the line II—II of Fig. 1,

Fig. 3 is a view, in side elevation, of a 40 modified form of resistor embodying my invention,

Fig. 4 is a view, in side elevation, of another modification of resistor embodying my invention,

Fig. 5 is a view, in side elevation, of a 45 further modification of a resistor embodying my invention, and

Fig. 6 is a view, in end elevation, of the resistor illustrated in Fig. 5.

An electric furnace, designated generally 50 by the numeral 11, comprises an outer metallic casing 12 which is provided with a plurality of supporting members 13 suitably secured thereto. An outer lining 14 comprises 55 a plurality of bricks or blocks of any suit-

able refractory heat-insulating material, usually employed in the art. An inner lining 15 comprises a plurality of bricks or blocks of a suitable refractory high-temperature-resisting material. The bricks or 60 blocks constituting the two linings 14 and 15 are so spaced and located as to provide a chamber which is divided into a work-receiving chamber 16 and a heating chamber 17, which chambers may be located in 65 any suitable or desired relation relatively to each other but are here shown as located in superposed position. A suitable refractory high-temperature resisting plate 18 is employed to separate the two chambers 16 and 70 17 from each other. A suitable opening 19 is provided in one of the walls of the furnace to permit of introducing material to be heat-treated into the chamber 16 and of removing it therefrom.

A heating element, which may be designated generally by the numeral 21, comprises a plurality of relatively thin, flat, refractory plates 22 which may consist of carbon or graphite or any similar resistance 75 material. In the form of heating element illustrated more particularly in Fig. 1 of the drawings, the flat plates 22 are maintained in spaced-apart relation at their upper ends by refractory resistor members 23 which are of substantially T-shape in lateral section. The overhanging portion of the members of T-shape insure that they will be supported in substantially the positions illustrated in Fig. 1 of the drawing during 80 the operation of the furnace. The area of cross-section traversed by an electric current is made relatively small by suitably reducing the height of the members 23. Any desired number of flat plates 22 and of the members 23, of T-shape, may be employed, 85 or as may be permitted by the longitudinal dimensions of the furnace chamber 17.

A suitable refractory conducting block 24 is located in operative engagement with the outer flat plate 22 at each end of the heating element, and is, in turn, operatively engaged by the inner end of an elongated refractory carbonaceous electrode 25. The outer tapering end of each of the electrodes 25 fits into a suitably shaped opening in a water-cooled electric-circuit-terminal member 26. An annular member 27, made of a suitable high-temperature-resisting electric-insulating material, such as certain forms of 100

asbestos, is located immediately adjacent the outer surface of the furnace wall and surrounding the water-cooled terminal member 26 in order to maintain it in its proper operative position and to prevent leakage of current therefrom into the metal casing 12.

Means for maintaining the plates 22 and the current-conducting and spacing members 23 in close operative engagement comprises a helical spring 28, the outer end of which engages a fixed member 29 which, as illustrated in Fig. 1, comprises a relatively heavy bent metal member, one end of which is secured to the metal casing 12. A rod 31, the inner end of which is threaded and is provided with an adjusting nut 32 and a washer 33, extends through the helical spring 28. The inner end of the rod 31 engages the outer surface of an insulating plate 34 which is located against the outer surface of the water-cooled terminal block 26. Any desired amount of pressure may be obtained by suitably adjusting the nut 32 on the threaded rod 31.

In order to stabilize the built-up heating element 21, a plurality of relatively small refractory blocks 35 are placed between each adjacent pair of plates 22 near the lower edge thereof. The thickness of the blocks 35 is substantially equal to that of the current-conducting spacing members 23 located at the top of the flat plates 22. Any desired material may be employed in making these spacing members 35, such as an electric-insulating refractory material or a material, such as charcoal, which is of relatively high electric resistance. If it is found desirable or necessary to employ electric-conducting spacing blocks adjacent the lower edge of the plates 22, the area of these is made very small and as few spacing blocks as possible are employed in order that the current traversing these blocks shall be relatively very small.

As illustrated more particularly in Figs. 1 and 2 of the drawing, the plates 22 may be of such dimension that their lower edges rest upon the floor of the heating chamber 17, in which case, it is necessary that the refractory material employed for the inner lining 15 shall be non-conducting even at the relative high temperatures experienced during the operation of such a furnace.

By employing a refractory diaphragm 18 and placing it between the work-receiving opening 19 and the carbonaceous heating element 21, the latter is protected against the oxidizing effect of air engaging the opening 19 during the operation of the furnace. The distance between the top part of the heating element 21 and the diaphragm 18 is made very small in order that the distance through which the heat from the heating element 21 must flow to reach

the work-receiving chamber 16 shall be as small as possible.

The relative locations of the heating chamber 17 and of the work-receiving chamber 16 may be any suitable or desired one, the main consideration being that the current-conducting spacing members hereinbefore described shall be so located between the adjacent flat plates 22 that the current path provided thereby is immediately adjacent the diaphragm 18 separating the two chambers from each other.

A modified form of heating element is illustrated in Fig. 3 of the drawing, in which the current-conducting spacing members comprise rectangular narrow flat bars 36 located adjacent one edge of the plates 22. Thin flat supporting members 37 are placed between the spaced plates 22 and are of such dimensions that they will extend from substantially the bottom of the bars 36 to the bottom of the plates 22. In constructing such a furnace, I have found it possible to use a piece of wood of suitable dimensions for the supporting member 37 which was changed into charcoal upon the initial heating-up of the furnace and which operated very satisfactorily as a supporting means for the bars 36.

Referring to Fig. 4 of the drawings, the plates 22 may be spaced apart at their upper edges by a relatively narrow mass 38 of granular current-conducting material, such as finely divided carbon or coke, and supporting members 37, as hereinbefore described in connection with the illustration described in Fig. 3, may be employed.

A plurality of small flat plates 39 may be employed as current-conducting members adjacent one edge of the plates 22 and a plurality of small blocks 35 as spacers adjacent another edge of the plates, a construction illustrated more particularly in Figs. 5 and 6 of the drawings. By this means, I still further reduce the area of the current path between the adjacent flat plates. A refractory plate 41 may be located beneath the plates 39, and a refractory bar 42 may be located beneath the blocks 35.

The device embodying my invention thus comprises a plurality of relatively thin, flat, refractory current-conducting plates which are separated by current-conducting spacing members of refractory material and of much smaller area of cross-section. The current-conducting spacing members may be located at any suitable or desired position on the plates to insure that the heat generated by a current traversing the path is generated adjacent a work-receiving chamber or adjacent a location in which the material to be heat-treated is placed.

This application is closely related to my co-pending application, Serial No. 454,776, filed March 23, 1921.

Various modifications and changes in detail and general arrangement may be made without departing from the spirit and scope of the invention and such modifications are intended to be covered by the appended claims.

I claim as my invention:

1. An electric furnace resistor comprising a plurality of relatively thin, flat, refractory plates, a plurality of current-conducting spacing members of relatively small area alternating with said flat plates, and means for maintaining said spacing members in proper operative positions relatively to said flat plates.
2. An electric furnace resistor comprising a plurality of relatively thin, flat, refractory plates, a plurality of current-conducting spacing members of relatively small area alternating with said flat plates and located adjacent the top portion thereof.
3. In an electric furnace, in combination, a heating element comprising a plurality of relatively thin, flat carbonaceous plates, having their flat surfaces located in spaced-apart relation relatively to each other, a plurality of current-conducting spacing members, of relatively small area, alternating with said flat plates, means for supporting said spacing members, and resilient compressing means for said plurality of plates and spacing members.
4. In an electric furnace, in combination, a plurality of refractory walls enclosing a furnace chamber, a carbonaceous diaphragm dividing said chamber into a heating chamber and a work-receiving chamber, a heating element in said heating chamber comprising a plurality of relatively thin flat, carbonaceous plates, a plurality of current-conducting spacing members, of relatively small area, alternating with said flat plates and means for maintaining said spacing members in proper operative positions relatively to said flat plates, and resilient compressing means for ensuring close operative engagement between said flat plates and said spacing members.
5. An electric furnace resistor comprising a plurality of relatively thin, flat, carbonaceous plates, a plurality of current-conducting spacing members of relatively small area alternating with said flat plates and located therebetween adjacent one edge thereof, and auxiliary spacing members of relatively high electrical resistance located between adjacent flat plates near another edge thereof.
6. An electric furnace resistor comprising a plurality of relatively thin, flat, carbonaceous plates, a plurality of current-conducting spacing members of relatively small area alternating with said flat plates and located therebetween adjacent one edge thereof, auxiliary spacing members of relatively high electrical resistance located between adjacent flat plates near another edge thereof, and resilient compressing means for maintaining said flat plates and said spacing means in close operative engagement with each other.

In testimony whereof, I have hereunto subscribed my name this 27th day of October 1922.

GEORGE M. LITTLE.
